(57) **CLAIM**

The ornamental design for an air dam for a vehicle bumper, as shown and described.

DESCRIPTION

FIG. 1 is a perspective view of an air dam for a vehicle bumper showing a first embodiment of our new design;

FIG. 2 is a second perspective view thereof;

FIG. 3 is a front view thereof;

FIG. 4 is a side view thereof;

FIG. 5 is an opposite side view thereof;

FIG. 6 is a rear view thereof;

FIG. 7 is a top view thereof;

FIG. 8 is a bottom view thereof;

FIG. 9 is a front view of an air dam for a vehicle bumper according to a second embodiment of our novel design which is identical to that shown in FIGS. 1–7 except it is a mirror image of said first embodiment; and

FIG. 10 is a side view of said second embodiment;

FIG. 11 is an opposite side view of said second embodiment;

FIG. 12 is a rear view of said second embodiment;

FIG. 13 is a top view of said second embodiment; and,

FIG. 14 is a bottom view of said second embodiment.

Parts shown in broken lines are for illustrative purposes only and form no part of the claimed design.
